UNITED STATES PATENT OFFICE.

FRED F. McCORMICK, OF XENIA, OHIO.

WINDOW-SASH.

1,143,640.

Specification of Letters Patent. Patented June 22, 1915.

Application filed February 16, 1914. Serial No. 819,058.

To all whom it may concern:

Be it known that I, FRED F. McCORMICK, a citizen of the United States, residing at Xenia, in the county of Greene and State of Ohio, have invented certain new and useful Improvements in Window-Sashes, of which the following is a specification.

My invention relates to storm fronts for vehicles and more particularly to a swinging window sash adapted to form a part of such storm front but which is also suitable for use in residences or factories or other constructions.

The object of the invention is to simplify the structure as well as the means and mode of operation of such devices, whereby they will not only be cheapened in construction, but will be more efficient in use, positive in their action, air and water tight and unlikely to get out of repair.

A further object of the invention is to provide a window sash which in its closed position will fit the frame sufficiently close to prevent rattle or chatter as the vehicle travels over a rough roadway and at the same time being capable of being easily and quickly withdrawn from closed position.

A further object of the invention is to provide a window so constructed as to prevent the seepage of water inward over the sill.

With the above primary and other incidental objects in view as will more fully appear in the specification, the invention consists of the features of construction, the parts and combinations thereof and the mode of operation or their equivalents as hereinafter described and set forth in the claims.

Referring to the drawings, Figure 1 is a perspective view of a portion of a vehicle to which a storm front embodying the swinging window sash forming the subject matter hereof, has been applied. Fig. 2 is a perspective view of a swinging sash window in open position, viewed from the inside. Fig. 3 is a vertical sectional view of the swinging window sash showing by dotted and dot and dash lines the window adjusted to different positions. Fig. 4 is a transverse sectional view of the window sash in its closed position. Fig. 5 is an enlarged transverse sectional view of one of the side bars of the window frame.

Like parts are indicated by similar char-

acters of reference throughout the several views.

In the drawings, 1 is a storm front of the vehicle embodying the swinging sash 2 forming the subject matter hereof. The swinging sash 2 is hinged at 3 along its upper edge to the frame 4. The sash and frame are preferably though not necessarily correspondingly rabbeted as indicated at 5 on the opposite vertical sides and if desired, across the top as shown in Figs. 3 and 4. It is not necessary that the frame and sash should be rabbeted upon their top edges even though the side rabbets are employed. The joint between the sash and frame is preferably protected upon the outside of the frame by weather strips 6 secured to the frame and overlapping the sash. These weather strips will prevent the rain beating through the crevices between the sash and frame even though the rabbets 5 are omitted.

The sill 7 of the frame 4 is beveled downward and outward as indicated at 8. This bevel may be of any desired angle, but it has been found in practice most convenient and desirable to form the bevel at an angle of substantially forty five degrees. The lower edge of the swinging sash 2 is beveled downward and outward as indicated at 9. Hinged to the lower edge of the sash 2 in such manner as to swing toward the outer side of the sash and in a direction the reverse of the movement of the sash 2 about its hinged connections 3, is a transverse strip 10, beveled on its upper edge 11 to correspond with the downward and outward inclination of the lower beveled edge 9 of the swinging sash and beveled on its lower edge 12 to correspond with the downward and outward beveled sill of the frame.

It is to be noted that the swinging sash 2 and the transverse strip 10 hinged thereto form a structure resembling and operating as a toggle link and further that the swinging sash approaches the sill 7 from the high side of the bevel 8. The swinging sash with the attached strip 10 is of such length that they can not pass over the high side of the beveled sill until the strip 10 is oscillated as shown by dotted lines in Fig. 3. The flexing of the transverse strip 10 about its hinged connection with the swinging sash permits the lower beveled edge 12 of the strip to pass over the high side of the sill 7, whereupon by pressing the sash 2 outward,

the sash is tightened in the frame by the toggle action of the sash 2 and strip 10 to prevent the rattle or chatter of the sash within the frame. By the toggle action, the 5 sash is further firmly seated on the top or cap of the frame and on the beveled face 11 of the strip 10, which in turn is firmly seated on the beveled sill 7 to exclude water and air from said joints.

10 When the sash and strip have been adjusted to a position upon a dead center or when the sash is in a plane common with the strip, the parts will retain their adjusted positions without the necessity of other locking means. However by providing slight clearance for the sash, whereby the sash and strip may be adjusted when in closed position to a point slightly beyond a dead center, such additional movement being so 15 slight as to be practically imperceptible, the sash will be securely locked in its adjusted position. When it is desired to open the sash, a slight pressure upon the outer side of the device adjacent to the hinged connection of the strip 10 to the sash 2 will release the sash, the strip 10 swinging upward to clear the upper edge of the beveled sill 7, whereupon the sash and strip may be oscillated upward to a position as indicated by 20 dot and dash lines, where they can be held by a suitable spring catch 13. It will thus be seen that the window may be readily released from the exterior of the vehicle without the necessity of climbing inside, which 25 is a convenience when the vehicle is in storage or when hitching a horse thereto.

Under ordinary conditions it will be found that the tension to which the sash and strip are subjected by their toggle like 30 action in the closing operation will be sufficient to prevent rattle or chatter within the frame. However if found desirable L shaped spring fingers 14 may be provided on the frame 4 on opposite sides of the 35 swinging sash 2, preferably at a point coincident with the beveled joint 9-11 of the sash 2 and the strip 10. These spring fingers by projecting between the sash and frame prevent side movement of the sash and 40 thereby obviate any chatter. The joint 50 9-11 between the sash 2 and the strip 10 and a joint 8-12 between the strip 10 and the sill 7 being inclined downward and outward, obviates any tendency of rain to seep 55 through these joints to the inside of the vehicle.

While the invention is herein shown and described as a part of a storm front for vehicles, it is to be understood that it is not 60 limited to such use, but may be employed for window construction generally, and is equally applicable to building constructions. Furthermore the sash might be arranged to 65 swing on a vertical axis without changing the construction other than to turn the

frame on its side. In such case the swinging section which oscillates about an axis parallel with that of the sash, will engage a vertical side of the frame. The portion of the frame so engaged is to be considered 70 as included in the term "sill" as herein used. I therefore do not wish to be understood as limiting the invention to its use with vehicles.

From the above description it will be apparent that there is thus provided a device of the character described, possessing the particular features of advantage before enumerated as desirable but which obviously is susceptible of modification in its 75 form, proportion, detail construction or arrangement of parts, without departing from the principle involved or sacrificing any of its advantages.

While in order to comply with the statute, 80 the invention has been described in language more or less specific as to certain structural features, it is to be understood that the invention is not limited to any specific details, but that the means and construction herein described comprise but one mode of putting the invention into effect, and the invention is therefore claimed broadly in any of its possible forms or modifications within the scope of the appended 85 claims.

Having thus described my invention, I claim;

1. A window comprising a frame provided with a beveled sill, a sash oscillating 100 about an axis parallel with the beveled sill and swinging to and from the side of the sill opposite the bevel face thereof, said sash being of greater extent than the opening of the frame and having a beveled edge 105 to engage the beveled face of the sill and a flexible joint in the sash permitting the beveled edge thereof to be passed over the sill into engagement with the beveled face thereof.

2. A window comprising a frame having a downwardly and outwardly beveled sill, a sash oscillating about an axis parallel with the beveled sill having a downwardly and outwardly beveled free edge, a swinging 115 section hinged to the sash having a downwardly and outwardly beveled top edge engaging with the beveled edge of the sash and a downwardly and outwardly beveled bottom edge engaging with the beveled sill. 120

3. A window comprising a frame, a sash comprising two sections hinged one to the other and occupying a substantially common plane when in closed position, and downwardly and outwardly beveled joints 125 between the sash sections and between the sash and frame.

4. In a window construction, a frame having a beveled sill, a sash hinged to the frame cap, said sash being beveled on its 130

lower edge, a swinging section hinged to the sash beveled on its upper edge to correspond with the beveled lower edge of the sash and beveled on its lower edge to correspond with the beveled sill.

5. In a window, a frame the sill of which is beveled downward and outward, a sash hinged to said frame to swing inward having its lower edge beveled downward and outward, said sash being of less extent than the window opening of the frame, and a swinging section hinged to the sash and having both edges beveled downward and outward to correspond with the beveled lower edge of the sash and the beveled sill.

10. A window comprising a frame, a sash hinged to the frame, a swinging section hinged to the sash, the hinged connections of the sash with the frame and the swinging section with the sash being parallel one with the other and oppositely disposed whereby said parts will swing about their

respective connections in opposite directions from normal position, the free edge of the swinging section being adapted to be 25 engaged with the side of the frame opposite the hinged connection of the sash, substantially as specified.

15. A downwardly and outwardly beveled sill, an inward swinging sash having a 30 downwardly and outwardly beveled lower edge parallel with its axis of oscillation, and a flexible joint in the sash likewise parallel with the axis of oscillation permitting the lowest edge of the sash bevel to pass 35 over the highest edge of the bevel of the sill.

In testimony whereof, I have hereunto set my hand this 30th day of January, 1914.

FRED F. McCALAIN.
